UNITED STATES PATENT OFFICE.

CHESTER W. TULLAR, OF DETROIT, MICHIGAN.

ENVELOP.

1,273,956.

Specification of Letters Patent. Patented July 30, 1918.

Application filed February 28, 1918. Serial No. 219,571.

To all whom it may concern:

Be it known that I, CHESTER W. TULLAR, a citizen of the United States, residing at Detroit, county of Wayne, State of Michigan, have invented a certain new and useful Improvement in Envelops, and declare the following to be a full, clear, and exact description of the same, such as will enable others skilled in the art to which it pertains 10 to make and use the same, reference being had to the accompanying drawings, which form a part of this specification.

My invention relates to envelops of the class designed to effect a saving in postage, 15 in which one of the flaps after sealing may be withdrawn for the examination of its contents whereby the postal authorities may determine if the character of the letter is such that it may be properly sent under a 20 reduced rate of postage.

One object of this invention is to effect a saving in the amount of paper used to construct an envelop of the character named, and while I am aware that envelops have 25 been made with an end flap having a hooked portion to secure it when sealed, the arrangement has been such that the blank must be cut from stock sufficiently wide to admit of the end flap overlapping when formed into 30 an envelop, in order that the hooked end of one flap may engage a gummed area on the overlapping flap. It will thus be evident that there is a considerable waste of material on each side of the flaps due to cutting a 35 blank with overlapping end flaps.

Another object of this invention therefore 40 is to effect a saving in the amount of stock used by cutting the blank from a relatively narrow sheet and providing one of its end flaps with a hooked portion adapted to engage an adhesive area formed on the lower flap of the envelop which also forms the major portion of the back of the envelop. Secured to the adhesive area on the lower 45 flap is a disk between which and the lower flap the hooked end flap is adapted to slide, it being thus seen that the disk and the wall formed by the lower flap serves as a guide to direct the hooked end of the flap into engagement with the adhesive area.

A further object of the invention is to provide means for guiding the hooked end of the flap toward the adhesive area with which the hooked portion interlocks.

55 With the foregoing and other objects in view which will appear as the description

proceeds, the invention resides in the combination and arrangement of parts and in the detail of construction hereinafter described and claimed, it being understood that 60 changes may be made in the precise embodiment of the invention herein disclosed without departing from the spirit of the same.

In the accompanying drawings which form a part of this specification:—Figure 65 1 is an elevation of an envelop “blank”, showing the gummed portions, and also the disk, which is partly broken away to expose the adhesive or gummed area beneath with which the hooked end of the flap is adapted 70 to engage.

Fig. 2 is a view of the envelop as it would appear before closing the upper or sealing flap.

Fig. 3 is an elevation of the blank of a 75 modification of the envelop shown in the preceding figure in which a guiding slot is provided in the end flap adapted to coördinate with an auxiliary adhesive area on the lower flap, whereby the hooked end of the 80 end flap may be guided into engagement with the adhesive area with which it is designed to interlock.

Fig. 4 is an elevation of the modification of the envelop before closing;—a blank of 85 which is shown in the preceding figure.

Referring now to the letters of reference placed upon the drawings:—

A, denotes an envelop blank. B, indicates the front of the envelop. C, denotes one of 90 the end flaps to which the lower flap D, is secured by means of the gummed or adhesive element E, applied along one edge of the latter. F, is an adhesive area, preferably circular in form applied to the lower 95 flap D, which serves a dual purpose, namely:—to secure the disk G, to the flap, and as the element with which the hooked end H', of the flap H, interlocks when the envelop is closed. I, indicates the upper flap 100 adapted to close over the lower flap D, and the end flaps C, and H. I', designates an adhesive area along the edge of the flap I, to engage the end of the flap I, with the end flap C, and lower flap D.

105 In the modification shown in Figs. 3 and 4, a relatively larger disk or strip G', is attached to the lower flap D, by two disconnected adhesive areas F, and F', adapted respectively to receive the hook H', in the end 110 of the flap H, and the flaring slot H², adjacent to the hook, the purpose of which is

to guide the hook H', into engagement with its co-acting adhesive area F, upon inserting the flap H, when closing the end of the envelop.

5 It will be readily understood that the wall of the disk or strip G', and the wall of the flap D, to which it is secured are held in spaced relation to each other by the interposed adhesive areas F and F', which thus 10 form a channel for the passage of the hooked flap H, between the disk and lower flap,— and therefore when the flap is inserted it is not apt to become entangled with papers lodged in the envelop.

15 It will also be apparent that by providing an extension of the disk or strip beyond the edge of the flap to which it is attached that the extension will serve to guide the hooked flap between the disk and the flap to which 20 the latter is secured.

By engaging the loose flap in the manner shown it is not apt to become disengaged upon inserting papers in the envelop before the sealing flap is closed.

25 Having thus described my invention what I claim is:

1. An envelop having a sealing flap, a side flap, and a bottom flap having overlapping portions, means for fixedly uniting parts of 30 said overlapping portions, a loose side flap opposite the fixed side flap having hooks formed by cutting away a portion of said loose flap, a disk, and means for securing said disk to one of the fixed portions of the envelop, said means being adapted to coöperate with the hooks of the loose side flap to secure the latter in its closed position.

2. An envelop having a sealing flap, a side flap, and a bottom flap having overlapping 40 portions, means for uniting parts of said overlapping portions together, a loose side flap opposite the fixed flap having a hook and also a guiding slot formed by cutting away portions of the loose flap, adhesive 45 areas disposed in spaced relation to each other upon the bottom flap adapted to co-ordinate with the hook and guiding slot of the loose flap, and a disk secured to the bottom flap by said adhesive areas and extending 50 beyond the edge of the bottom flap,

whereby it may assist in guiding the loose flap between the bottom flap and said disk and into engagement with the adhesive areas.

3. An envelop having a sealing flap, a bottom flap extending upwardly to a point adjacent to the fold of the sealing flap, and a relatively short side flap having overlapping portions, means for fixedly uniting parts of the overlapping portions of the respective 60 flaps together, a loose side flap opposite to the fixed side flap having hooks and also a guiding slot formed by cutting away portions of the loose flap, a plurality of adhesive areas disposed in spaced relation to each other near the edge of the bottom flap adjacent to the end of the envelop carrying the loose flap, and a disk secured to the bottom flap by the adhesive areas and overlapping the edge of said bottom flap, whereby 65 it may serve to guide the loose flap between the bottom flap and the disk and into engagement with the adhesive areas.

4. An envelop having a sealing flap, a bottom flap extending upwardly with a relatively wide edge paralleling and extending adjacent to the fold of the sealing flap, a relatively short side flap having portions which overlap the bottom and sealing flaps, means for fixedly uniting said overlapping 80 portions together, a loose side flap opposite the fixed flap having hooks and a guide slot formed by cutting away portions of the loose flap, said loose flap adapted to overlap the bottom and sealing flaps but not the 85 fixed side flap, a plurality of adhesive areas disposed in spaced relation upon the bottom flap adjacent to the end carrying the loose flap, and a disk or strip secured to the bottom flap by said spaced adhesive areas and 90 overlapping the edge of the bottom flap, whereby it may serve to guide the loose flap into engagement with the adhesive areas.

In testimony whereof, I sign this specification in the presence of two witnesses.

CHESTER W. TULLAR.
